DESIGN FOR A CASKET ILLUMINATING LAMP

William M. Parker, Sr., Granite City, Ill.

Application August 28, 1939, Serial No. 86,912

Term of patent 14 years

To whom it may concern:

Be it known that I, William M. Parker, Sr., a citizen of the United States, residing in the city of Granite City, county of Madison, and State of Illinois, have invented a new, original, and ornamental Design for a Casket Illuminating Lamp, of which the following is a specification, reference being had to the accompanying drawing, forming a part thereof.

In the drawing:

Fig. 1 is a front elevation of a casket illuminating lamp showing my new design; Fig. 2 is a side elevation of the lamp, and Fig. 3 is a top plan view of the lamp shown by Figs. 1 and 2.

I claim:

The ornamental design for a casket illuminating lamp, substantially as shown.
